UNITED STATES PATENT OFFICE.

ROY V. COLLINS, OF NEW YORK, N. Y., ASSIGNOR TO AMERICAN AUTOMATIC SWITCH COMPANY, OF NEW YORK, N. Y., A CORPORATION OF NEW YORK.

ELECTRIC SWITCH.

1,070,777.

Specification of Letters Patent. Patented Aug. 19, 1913.

Application filed July 14, 1909. Serial No. 507,465.

To all whom it may concern:

Be it known that I, Roy V. Collins, a citizen of the United States, and a resident of the borough of Manhattan of the city of New York, in the county and State of New York, have invented certain new and useful Improvements in Electric Switches, of which the following is a specification, reference being had to the accompanying drawings, forming a part hereof.

The improvements relate particularly to that type of electric railway switch in which two magnets are provided for moving the switch tongue, one for moving the tongue in one direction and the other for moving the tongue in the opposite direction. These switches are usually employed with a line contact breaker, which is a device located upon the trolley wire and through which current is delivered to the switch mechanism and also to the car as the trolley passes over the same. Thus, through the medium of the line contact breaker, the motorman is able to control the position of the switch tongue, as he approaches it, by drawing current into the car, or by coasting along as the trolley rides upon the line contact breaker, according as he may desire the switch tongue to occupy one position or the other.

One object of the present improvement is to provide a simple mechanism to be interposed between the line contact breaker and switch tongue whereby the latter may be moved quickly and surely into its proper position, upon the delivery of current to said mechanism.

Another object is to provide the mechanism with an improved sealing device so related to the switch tongue as to prevent the entry of mud and water into the box containing said mechanism.

In the drawings: Figure 1 is a diagrammatic view of the improved mechanism and the circuits involved therein. Fig. 2 is a view in longitudinal section through a box containing most of the switch mechanism. Fig. 3 is a view in transverse section through the same box. Fig. 4 is a view in elevation of a pole box with the cover open containing some of the switch mechanism, and, Fig. 5 is a view in transverse section through said box.

Referring first to the diagram in Fig. 1,

it will be seen that the line circuit breaker 55 is indicated conventionally at *a* and the two switch operating magnets, one for moving the switch tongue in one direction and the other for moving it in the opposite direction, at *b* and *b'* respectively. Leading from a 60 conductor on the line circuit breaker in electrical contact with the trolley wire is a circuit *c* which includes a fuse *m* and a solenoid *e*, said circuit being bridged by the trolley wheel as the latter passes over 65 the plates *a'* and *a''* of the line circuit breaker. Continuing, said circuit extends through a fuse *f* and then divides into three paths branching from the point *g* as follows: path 1 leading through contacts *h* to magnet *b'* and thence to ground; path 2, leading 70 through contacts *n* to magnet *b* and thence to ground; and path 3, leading through contacts *s* to magnet *b'* and thence to ground. Contacts *h* are normally bridged by a contact switch *h'* attached to the core of the solenoid *e* and when the mechanism is not 75 in operation this switch rests down by gravity upon contacts *h*. Contacts *n* are normally bridged by a pivoted arm *n'* 80 which, when the mechanism is not in operation, rests down by gravity upon these contacts, and which is adapted, when the energization of the solenoid is sufficient to raise it, to bridge the contacts *s*.

The operation of the device is as follows: When the trolley bridges the plates *a'* and *a''* of the line circuit breaker, current will be delivered over the circuit *c* and, as the parts are in the position shown in figure 90 when the trolley reaches the line circuit breaker, the current will follow both the paths 1 and 2 and deliver current into both magnets *b* and *b'*. Immediately, however, as this condition is established, the solenoid *e* will operate to lift the contact switch *h'* and break the circuit through path 1 whereby the magnet *b* will become operative and move the switch tongue. This latter condition is dependent however upon the switch arm *n'* remaining down upon the contacts *n* to preserve the continuity of the circuit through path 2. If the solenoid *e*, on the other hand, were strong enough to raise the arm *n'*, then the circuit would be closed 100 through path 3 and opened through path 2, whereby current would be delivered to magnet *b'* and the switch tongue moved in the 105

opposite direction. Now, the solenoid *e* will or will not be strong enough to raise the arm *n'*, according as the motorman does or does not deliver current to the car when the trolley rides upon the line circuit breaker; for when the car takes current the amperage of the current through the solenoid will be considerably greater (since not only does the current which passes through the magnet *b* or *b'*, whatever the case may be, pass through the solenoid *e* but also the current that passes through the car, as current can pass through the car, when the trolley wheel is on the strips *a'* and *a²*, only by passing through the solenoid *e* since the plates or strips *a'* and *a²* on which the trolley wheel rests are insulated from the trolley wire) than when the car is not in circuit as it is obvious that the only current passing through the solenoid *e*, at that time, is the current passing through magnet *b* and therefore the resistance of the circuit is accordingly much greater.

The advantage of employing the connection represented by path 1 is that the switch tongue will always commence to move in the right direction, for in this way current will first be delivered to both magnets *b* and *b'*, and then cut out of the one which should remain inoperative during the throw. In other systems, it often happens that the parts are left, upon the preceding actuation of the switch, so that upon the next actuation a momentary current will be delivered into the wrong magnet and start the switch tongue in the wrong direction. This is an undesirable feature of this type of switch and should be avoided.

Referring now to Figs. 2 and 3, it will be seen that the magnets *b* and *b'* are inclosed in a box and that the common core of these magnets is operatively connected to a vertical shaft *d* the upper end of which extends through the cover of the box for connection with the switch tongue. In my U. S. Letters Patent No. 908647, dated January 5, 1909, there is shown and described a seal for the upper end of this shaft to prevent the entrance of moisture and dirt into the box. In the present case the walls of the cup *i* containing the mercury forming the seal are built up above the cover and the upper edge of the cup is above the level of the lower or under side of the switch tongue. In this way the moisture and dirt which enters around the top of the shaft is kept from working into the sealing cup, for the bank of mud which forms up to the level of the bottom of the switch tongue is swept out before it reaches the top of the cup. The annular projection *h* secured to the top of the shaft *d* is provided to enter the cup as in the case of the apparatus described in said Letters Patent. With the exception of the above the construction for separating the switch

tongue from the core of the magnets *b* and *b'* is substantially the same as that shown and described in said Letters Patent.

Figs. 4 and 5 show a specific embodiment of the current controlling member comprising the solenoid *e* and movable contacts separated thereby and these figures illustrate how part of the improved mechanism such as the fuse and the solenoid *e* may be located in a pole box above the ground as will be readily understood. The current comes in over line 1 through fuse *m*, passes through solenoid *e*, over line 2 onto plate *a'*, from thence through trolley wheel onto plate *a²* thence to line 3, through fuse *f* where current goes momentarily through contacts *h* and *n* but, when the current is "off" in the car, immediately upon the solenoid *e* becoming energized *h'* is lifted, opening circuit at *h* and allowing the circuit to be completed through magnet *b*. Now when the current is "on" in the car the same thing occurs except that the current passing over wire 1, fuse *m*, solenoid *e* and wire 2 is much greater as not only does the current just described pass over these wires but also all the current that goes through the car; therefore the current passing the solenoid *e* being so much greater in this case, not only lifts *h'* but is sufficient to also lift *n'* and thereby open circuits at *n* and *h* and complete a circuit at *s* which energizes magnet *b'*.

I claim as my invention:

1. The combination with a switch tongue, of a mechanism for operating said tongue, said mechanism including a sealing cup with sides extending above the level of the underside of said tongue.

2. The combination with a switch tongue, of a box, operating mechanism for the switch tongue in said box, a shaft extending through the top of said box and operatively connecting said mechanism and the switch tongue, a cup around the shaft and having sides extending above the top of the box to a level above the underside of the switch tongue, and an annular projection upon the shaft extending down into the cup.

3. The combination of a housing, a movable switch member, operating means therefor in the housing, means connecting the operating means and movable switch member, said connecting means comprising a movable member which extends through the housing, the housing carrying a member which surrounds the movable member, extending through the housing, and which extends above the bottom of the movable switch member, and a liquid seal between the movable member and the member surrounding the same.

4. The combination with a switch tongue, of a mechanism for operating said tongue, said mechanism comprising an operating lever, a movable member therefor within a

housing, an annular member surrounding the movable member and carried by the housing said annular member extending above the free end of the lever and a liquid seal between the housing and movable member.

5. The combination of a conductor, plates or members insulated therefrom, electrically operated means to move contact members, 10 said means electrically connected to the conductor and one of the plates or members, a second and third electrical operating means, three contact members the first and third of which are electrically connected to the second 15 operating means, the second of which is electrically connected to the third electrical operating means, means to electrically connect the second plate or member with the three contact members, said means comprising 20 movable contact members operated by the first mentioned electrical operating means; the parts being arranged to operate as follows, when the plates are not electrically connected and therefore no current is passing 25 through the first mentioned operating means the circuits having the first and second set of contacts will be closed; when the plates are electrically connected current will pass through the first mentioned operating 30 means sufficient to cause the opening of the circuit having the first set of contacts by the movement of the movable member therein; and when the plates are electrically contacted and a comparatively large amount of 35 power is being withdrawn therefrom the first mentioned electrical operating means will receive a larger amount of current than heretofore and will open the circuits having the first and second set of contacts by moving 40 the movable members in said sets and will close the circuit having the third set of contacts by moving the movable member thereof.

6. The combination of a conductor; members or plates insulated from the conductor, 45 three sets of contacts comprising contact members referred to as contacts number one, number two and number three; electrical operating means for opening and closing circuits; and a second and also a third electrical operating means; the different elements 50 of the combination being connected as follows, the first mentioned electrically operating means to and between the conductor and

one of the plates; the other plate to one 55 member of each of the contact members; the second electrical operating means to the other members of contacts one and three; the third electrical operating means to another member of contact two; the first mentioned electrical operating means opening 60 and closing the circuits including the contact sets as follows, when the plates are not electrically connected circuits having contact sets one and two are closed; when the 65 plates are connected without power being drawn therefrom for use of means other than those mentioned the first mentioned operating means operates to open the circuit having the first set of contacts but leaves the 70 circuit having the second set of contacts closed; and when the plates are electrically connected and power is withdrawn therefrom for means the current passing through the first mentioned operating means will be 75 sufficient to cause the opening of the circuits having contacts one and two and will close circuit having contact three.

7. The combination with a switch point 80 of a box having an intermediate horizontal partition extending the full length and width of the box, a vertical shaft which passes through said partition, the upper end of which shaft is operatively connected to the switch point and the lower end of which 85 is operatively connected with operating mechanism located below the partition but within the box, a liquid seal cup surrounding the shaft, the sides of which cup extend above the partition. 90

8. A street box containing switch point operating means, said box having an upper portion and a lower portion separated by a water-tight partition, electrical operating means in the lower portion of the box, a 95 shaft extending from the lower to the upper portion through said partition, and means for preventing dirt and moisture from entering the lower chamber, said means comprising a liquid seal and a flange or annular member extending above the upper surface of the partition. 100
